United States Patent [19]

Yubisui et al.

[11] Patent Number: Des. 315,358

[45] Date of Patent: ** Mar. 12, 1991

[54] ELECTRONIC CALCULATOR WITH
PRINTER

[75] Inventors: **Takahisa Yubisui; Hiroshi Sakaguchi;**
Keiichi Koyama, all of Osaka, Japan

[73] Assignee: **Sharp Corporation**, Osaka, Japan

[**] Term: **14 Years**

[21] Appl. No.: **210,127**

[22] Filed: **Jun. 23, 1988**

[30] Foreign Application Priority Data

Dec. 29, 1987 [JP] Japan 62-53603

[52] U.S. Cl. **D18/7; D18/2**

[58] Field of Search D18/2, 6, 7, 11;
D14/100, 107, 111, 114, 115; 364/706-710

[57] CLAIM

The ornamental design for an electronic calculator with
printer, as shown and described.

DESCRIPTION

FIG. 1 is a top plan view of the electronic calculator
with printer showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a right front and top perspective view thereof.
